DRUM TYPE DRIER

Emil Kaessmann, Leverkusen-I., G. Werk, Germany, assignor to I. G. Farbenindustrie Aktiengesellschaft, Frankfort-on-the-Main, Germany

Application July 5, 1935, Serial No. 29,972
In Germany August 12, 1933

2 Claims. (Cl. 257—98)

This invention relates to a novel drum type drier.

The drum driers hitherto used in the chemical industry for the purpose of drying paste-like or dissolved substances, are completely closed hollow cylinders, the horizontal dimensions of which are always greater than their vertical measurements. As a rule, the driers are heated by means of steam of comparatively low pressure, since the mantle 10 of the drum is usually made of cast iron. Wrought iron and refined steels, if worked into a sufficiently rigid cylinder, are too expensive.

Due to their dimensions, these driers exhibit disadvantages and difficulties which especially 15 manifest themselves in insufficient utilization of the heating medium and of the heat exchanging surface to which it is applied. Thus the hollow body of the cylinder reduces the flow velocity of the heating medium; air which collects diminishes the drying efficiency, and the condensed water at the bottom of the cylinder eliminates 20 part of the heat exchanging surface from operation. It is also known that the effective drying surface of such cylinders is never fully utilized, 25 because the substances to be dried cannot be spread uniformly thereon.

Furthermore, the temperature range which may be applied to the drying surfaces is limited, due to the structure of cast iron which for 30 bids the application of high steam pressure for reasons of safety.

Removal of the dry material from the mantle by means of a scraper is likewise difficult, particularly when the smooth surface is injured by 35 the scraping effect of the knives.

It has been found that these drawbacks can be remedied by shaping the aforementioned hollow cylinder into a drum, having a horizontal axis which is shorter than the vertical diameter of 40 the drum, i. e. the proportion of vertical diameter to horizontal axis must be at least two to one and not more than ten to one. It has been ascertained that the inner surface of the drum mantle can be heated by means of tubes welded thereto, into and from which tubes the heating agent, evenly distributed over the entire circumference, is introduced and discharged. Due 45 to this modification of the hitherto known working conditions, considerable advantages arise 50 with respect to construction of the drums.

Thus, even distribution of the heating agent is readily possible owing to the large vertical diameter and short mantle of the drum. The outer part of the mantle of the drum may be built 55 without regard to the amount of steam pressure

applied and yet it will not be exposed to the danger of warping, since the inner parts of the drum such as the tubes supporting the mantle which do not participate in the drying process, can be given any required stability. Therefore, 5 materials which are not suitable for the hitherto used hollow cylinders, for instance, wrought iron and refined steels, are preferred in the present invention.

Further advantages become obvious in the 10 practical use of the new drum driers. Charging of the material to be dried upon a mantle which is so greatly reduced in length proceeds without difficulty, likewise discharging of the dry material. It is feasible to spread the wet material in 15 a rather thick layer upon the surface of the mantle, thus allowing gentler treatment of the surface during scraping, since it is known that the dry material adheres the less rigidly to the mantle the thicker the layer is in which it is 20 applied thereto.

The heat exchange is most efficient because of the very rapid velocity of the flow of steam through the tubes, and due to the reduced thickness of the outer wall of the mantle. The possibility of covering the mantle evenly and completely with the material to be dried warrants a 25 satisfactory heat balance which is supported by the ready and sufficient insulation of all parts of the device not utilized in the drying process. 30

In summary it may be said that the advantages of the present invention over the known drum driers reside in simplified construction which yields an equal drying effect upon an essentially smaller heating surface. For instance, my novel 35 drum drier possessing a surface of 6 square meters equals a cylindrical drier used heretofore, which is directly heated with steam and which has a drying surface of 24 square meters.

The new drier is operative not only for drying 40 materials by means of a heating medium, as suggested, but also for the manufacture of ice from water by using, for instance, a cool brine as heat exchanging medium.

In the accompanying drawings one embodiment 45 of my new drum drier is illustrated by way of example.

Fig. I represents a central transverse vertical section of a drier according to the invention. The drier consists of a mantle 1, to which the 50 heating system 2 is spirally welded in the form of tubes. The charge and discharge of the heating medium is effected through chambers 4 provided within the shaft 3. The chambers are connected with the two ends of the heating coils 55

2 by radially arranged spoke-like tubes 5. Inlet and outlet to and from the chambers 4 is effected by means of connecting tubes 8 and 9, which are tightened by co-operation with stuffing boxes 6 in the bore holes 7 of the shaft 3. The shaft 3 is provided with bearings of the customary construction at point 10.

Figure II is a sectional view taken on the line 2-2 of Figure I. In Figure II a device 11 is to be seen by means of which the material to be dried is spread onto the drum. 12 illustrates a scraping knife by which the dried material is taken off from the drier. 13 represents the layer of the material to be dried.

15 I claim:—

1. In a drum type drier for drying paste-like or dissolved substances, in combination, a drying cylinder having a horizontal hollow shaft, the

vertical diameter of said cylinder being at least twice and not more than ten times as large as its horizontal dimensions, a system of spiral tubes welded to the inner surface of the mantle of the cylinder and serving as conductor for a heating medium, inlet and outlet chambers in said hollow shaft for said heating medium, means for connecting said system of spiral tubes to said chambers, means for feeding material to be dried to the outer surface of said cylinder, and means for removing said material from said cylinder when dried.

2. A drum drier as claimed in claim 1 in which the means for connecting the system of spiral tubes to the chambers consists of a plurality 15 radially arranged spoke-like tubes.

EMIL KAESSMANN.
